N. HERZOG

SIGN

Filed April 12, 1920

UNITED STATES PATENT OFFICE.

NATHAN HERZOG, OF CHICAGO, ILLINOIS.

SIGN.

Application filed April 12, 1920. Serial No. 373,051.

To all whom it may concern:

Be it known that I, NATHAN HERZOG, a citizen of the United States, residing at Chicago, in the county of Cook and State of Illinois, have invented a certain new and useful Improvement in Signs, of which the following is a specification.

This invention relates to signs for streets and highways, and has for its object 10 to provide a new and improved sign of this description. The invention has among other objects to provide a sign for automobile drivers and which can be placed along streets and highways at desired 15 points so as to display signals or signs for the guidance of such automobile drivers. The invention has other objects which are more specifically pointed out in the following description. Referring now to the 20 drawings

Fig. 1 is a side elevation of one form of device embodying the invention;

Fig. 2 is a sectional view taken on line 2—2 of Fig. 1;

Fig. 3 is a sectional view taken on line 3—3 of Fig. 1;

Fig. 4 is a sectional view of the post showing a modified construction.

Fig. 5 is a sectional view of the post 30 showing a further modification.

Like numerals refer to like parts throughout the several figures.

In carrying out the invention I provide an upright post 1 which may be made up 35 to carry the sign or other indication. In the construction shown this post is made up of a series of outer angle irons 2, and a series of inner angle irons 3, these angle irons being connected by the braces 2^a. The 40 post has a base 4 which may be mounted upon a cement base 5 and attached thereto by the fastening devices 6 which pass through the flanges 7 on the post base. The base of the post may be provided with some 45 such sign as for example the warning sign "Stop," where the post is placed at intersections or other points where the warning "Stop" is desirable. This sign is made up of letters which may be illuminated 50 at night. When the driver of an automobile is passing along the street or highway, his eye is on the surface ahead over which he is about to pass, and a red light at the top of a post for example is apt not to be

seen by him, and this is particularly true 55 where the automobile has a top. By placing this sign "Stop" at the bottom and providing means for showing a red light at the bottom it will be seen that this danger signal cannot escape his notice and it is 60 placed where his eye must see it. I prefer therefore to arrange the letters so that when a light is placed back of them the red light will show.

The post 1 is also provided with letters 65 which may be illuminated at night and which set forth the desired information. For purposes of illustration I have used the word "Boulevard" made up of a series 70 of letters. These letters may be placed on all sides of the post. At the top of the post I may provide a light 8, such as a red light, or light of any other color. The red light will particularly be used where a danger 75 signal is desired.

I prefer to make the letters so that they can be easily removed and replaced so that various signs may be arranged for any given post, thus permitting the post to be 80 made up in stock and the desired sign applied thereto as is required. It also happens for example that these posts are run into by automobiles and the lower letter or letters broken, and hence by means of this removable construction these broken letters may be easily, quickly and cheaply removed and replaced. For this purpose I prefer to arrange the letters upon removable pieces 9, 10 and 11. Each piece may have a single letter as the piece 9, or each 85 piece may have a plurality of letters, as the pieces 10 and 11. These pieces may be fastened to the frame by any suitable fastening devices. It will thus be seen that the letter holding pieces may be removed 90 and letter holding pieces having other letters may be easily and quickly placed in position, thus permitting any desired sign to be used and also permitting the sign to 95 be changed as desired.

In the construction illustrated in Figs. 1 and 2 the edges of the plates carrying the letters engage the angle irons 12 and are fastened thereto by the fastening devices 12^a.

In Fig. 4 I have shown a construction 105 where the angle irons 3 have projecting ends 3^a which extend beyond the ends of

the angle irons 2. The letters may then fit in between the opposed edges of the angle irons 2 and may be fastened to the projecting edges 3^a of the angle irons 3 by screws 5 or other fastening devices 3^b.

In Fig. 5 I have shown a construction where there are cross pieces 14 at suitable intervals, and these cross pieces are provided with letter receiving grooves or spaces 10 15 and the plates carrying the letters will then be slid in position and fastened by screws 16 to the cross pieces 14.

I prefer to provide some means for illuminating the letters at night. This may be 15 done by placing a series of lights 17 inside of the post. Any desired number of lights may be used. I may place one back of each letter, or one for a series of letters, depending upon the result desired. These letters 20 are arranged with glass behind them preferably opaque so that the light will shine through. As herein illustrated the base 4 which is larger than the post may be provided on the top with a series of pieces 18 25 of glass and one or more lights 19 may be located in this case. It will thus be seen that light will then be thrown upward from this base and I prefer to arrange the base so that this light will be red thus increasing 30 the conspicuousness of the danger signal at the bottom of the post.

I claim:

1. A sign for streets and highways comprising a post having a hollow metal frame work and a series of letters removably fastened to said frame work and arranged so that said letters may be removed and replaced to provide the post with any desired sign, said post provided with an enlarged base, letters thereon extending across below the letters on the post, the letters on the base reading substantially at right angles to the letters on the post.

2. A sign for streets and highways comprising a post having a frame work and a series of letters removably fastened to said

frame work and arranged so that said letters may be removed and replaced to provide the post with any desired sign, and means at the base of said post for showing 50 a danger signal.

3. A sign for streets and highways comprising a post having a frame work and a series of letters removably fastened to said frame work and arranged so that said letters may be removed and replaced to provide the post with any desired sign, an enlarged base for said post, said base provided at its upper face at the sides of said post with light transmitting material, and a light 55 60 in said base arranged so that the light shines up along the post.

4. A sign for streets and highways comprising a post having a series of letters thereon, an enlarged base for said post, said base having a laterally extending glass top which projects beyond the post, an illuminating device in said base adapted to direct light up along said post.

5. A sign for streets and highways comprising a post having a series of letters thereon, an enlarged base for said post, the post extending upwardly from a point in the middle of the base, said base provided with glass at the top thereof surrounding 70 75 said post and extending laterally with relation to the post, said base having letters at the side thereof reading substantially at right angles to the letters on the post, and means within the post for illuminating the 80 letters on the post.

6. A sign for streets and highways comprising a post having a frame work made up of a series of angle irons separated by spaces, cross braces connecting said angle irons, letter plates connected with said angle irons and extending across the spaces between them, and means for illuminating said letters so they show at night.

Signed at Chicago county of Cook and 90 State of Illinois, this 8th day of April, 1920.
NATHAN HERZOG.
